UNITED STATES PATENT OFFICE.

JAMES K. CULLEN, OF NEW YORK, N. Y., ASSIGNOR TO NILES-BEMENT-POND COMPANY, OF NEW YORK, N. Y., A CORPORATION OF NEW JERSEY.

AUXILIARY TOOL SUPPORT.

Application filed October 8, 1921. Serial No. 508,401.

To all whom it may concern:

Be it known that I, JAMES K. CULLEN, a citizen of the United States, residing at New York, in the county of New York and 5 State of New York, have invented certain new and useful Improvements in Auxiliary Tool Supports, of which the following is a specification.

This invention relates to boring mills and 10 like machines and particularly to an auxiliary tool supporting column adapted to be removably secured to the bed of the machine and to extend upwardly adjacent the table thereof. In machines of this type a supplemental tool for performing certain operations on the work is often of considerable 15 advantage. It is accordingly a primary object of the invention to provide in combination with a boring or like machine 20 an auxiliary tool supporting column adapted to be removably and rigidly secured to the bed of the machine beneath the work table and to extend preferably in a vertical direction to one side of and above the table 25 in a manner to support a tool thereon in a work engaging position.

Another object of the invention is to provide an auxiliary tool support for boring mills and the like comprising a base portion 30 adapted to be removably and rigidly secured to the bed of a boring mill, a column portion, tool supporting means on the column and means for feeding the tool vertically and horizontally either simultaneously or 35 independently as desired.

With these and other objects in view, my invention consists in the features of construction and operation set forth in the following specification and illustrated in the 40 accompanying drawing. In such drawing annexed hereto and forming a part of this specification, I have shown certain embodiments of my invention as applied to a boring mill but it will be understood that the 45 invention can be otherwise embodied and that the drawing is not to be construed as defining or limiting the scope of the invention, the claims appended to this specification being relied upon for that purpose.

50 Referring to the figures of the drawing:

Figure 1 is a partial front elevation of a boring mill having the present invention applied thereto.

55 Fig. 2 is a fragmentary side elevation thereof.

As stated above, the object of the invention is to provide an auxiliary tool support for boring mills or like machines. The construction of the support is preferably in the form of a column having a base adapted to 60 be mounted on and secured to a pad or cheek formed on the bed of the machine. Except for such pad or cheek, the construction of the machine preferably remains unaltered. The cost of providing this cheek on standard machines, as manufactured, is negligible but fully equips all such machines for receiving the auxiliary tool support thereon. Furthermore, the expense of such additional equipment to the shop is comparatively small 70 since a single attachment ordinarily is sufficient to care for several machines. It may furthermore be stated that the auxiliary support is so mounted on the machine that it in no way interferes with the usual operation thereof. 75

Referring more specifically to the figures of the drawing by reference characters, 1 indicates the bed of a boring mill, 2 the rotary table thereon and 3 and 4 the usual 80 vertical uprights on the bed. A cross rail 5 with tool supports 7 and 8 thereon, as illustrated, is mounted on the uprights. The subject matter of the present invention is an auxiliary tool supporting column particularly adapted to be used in combination with a machine of the type just described, such auxiliary column with the tool supporting and operating means combined therewith being illustrated in the drawing as remov- 85 ably secured to a pad or cheek on the bed 1. This auxiliary construction will now be described. 90

The auxiliary tool supporting column comprises a base 10 having a column 11 extending preferably vertically therefrom to a position adjacent and above the table 2. The bed 1 of the boring mill is illustrated as provided with a cheek 12 to which the corresponding supporting portion 13 of the base 100 10 is secured. Bolts 14 and a tongue and groove connection 15 serve to rigidly secure the auxiliary tool support to the bed 1.

A tool supporting saddle 16 is vertically 105 slideable on the column 11 and a tool bar 17 is mounted for horizontal sliding movement on the saddle, preferably radially of the table 2. It will be understood that the saddle and tool bar can be fed on their respective supports in any manner and by any 110

means desired. In the drawing, I have illustrated such members as being fed from a feed motor 18.

- 5 A screw 19 and a feed shaft 20 are mounted vertically in the column 11. The screw engages a nut 21 on the saddle for moving the saddle vertically. The feed shaft is operatively connected to a rack 22 on the tool bar through a train of gearing 23, 24, 25 and 10 26 and a pinion 27, the gear 23 being splined to the feed shaft and the pinion 27 engaging the rack for axially moving the bar horizontally in the saddle, preferably radially of the table 2.
- 15 A horizontal shaft 28 is operatively connected to the motor through intermeshing spur gears 29 and 30. Bevel gears 31 and 20 32 loose on the shaft 28 are respectively in mesh with bevel gears 33 and 34 on the screw and feed shaft. Bevel gears 31 and 32 each extend through a supporting bearing and are provided with clutch portions 35 and 36 respectively on the other ends thereof. Clutches 37 and 38 are splined to the shaft 25 28 and are adapted to be shifted therealong to engage the clutch portions 35 and 36 respectively to drive the screw and feed shaft from the motor. Hand levers 39 and 40 are provided for shifting the clutches 37 and 38.
- 30 Briefly, the operation of the machine is as follows: When the operator desires the use of an auxiliary tool, as heretofore stated, he secures the auxiliary tool supporting column to the cheek 12 of the boring mill or like machine. The saddle 16 may then be moved vertically to the desired elevation by means of the motor 18, screw 19 and the intermediate connections heretofore described. The tool bar 17 also may be moved horizontally in the saddle to the desired position through the feed motor and the operative connections therefrom to the rack 22. With the tool thus set to the proper position, the same may be fed in the tooling operation 40 either horizontally or vertically or both through the before described feeding connections from the motor. It will be understood that the feeding operation of the motor may be controlled in the usual manner. By referring to Fig. 2, it will be seen that the auxiliary column 11 is sufficiently spaced from the main column 4 to avoid any interference with the cross rail 5 and the tool supports thereon. The auxiliary tool supporting means therefore operates to perform the desired function without in any way interfering with the usual and normal operation of the machine. For the reason last stated, it may often be desirable to use this auxiliary tool supporting means in lieu of the usual side head mounted on one of the main uprights beneath the cross rail. As is well known, such side head positively prevents the lowering of the cross rail to its lowermost position on the uprights.

What I claim is:

1. In a boring mill, the combination of a bed, a work table rotatably mounted thereon, a vertically extending upright adjacent the table, tool supporting means carried by the upright, the bed being provided with a supporting cheek on one side thereof, an auxiliary tool supporting column removably and rigidly secured to the said cheek on the bed of the machine beneath the work table and 70 extending upwardly to a position adjacent and above the table, a tool supporting saddle carried by the column, a tool holder carried by the saddle, and means for moving the saddle along the column and the tool 75 holder in the saddle.

2. In a machine of the class described, the combination of a bed, a work table movably mounted thereon, a vertically extending upright adjacent the table, tool supporting means carried by the upright, an auxiliary tool supporting column removably and rigidly secured to the bed of the machine beneath the work table and extending vertically to a position adjacent and above the 80 table, a tool supporting saddle carried by the column, a tool holder carried by the saddle, and means including a feed motor on the column for feeding or traversing the saddle vertically on the column and the tool 85 holder in the saddle either simultaneously or independently.

3. In a boring mill, the combination of a bed, a work table rotatably mounted thereon, a pair of spaced uprights adjacent the table, a cross rail mounted on the uprights, a tool supporting saddle carried by the cross rail, an auxiliary tool supporting column removably and rigidly secured to the bed of the machine beneath the work table and extending upwardly to a position adjacent and above the table, the bed being provided with a supporting cheek for receiving the column thereon, a tool supporting saddle carried by the column, a tool holder carried by the saddle, and power operated means for moving the saddle along the column and the tool 100 holder in the saddle.

4. In a boring mill, the combination of a bed, a work table rotatably mounted thereon, a pair of spaced uprights adjacent the table, a cross rail mounted on the uprights, a tool supporting saddle carried by the cross rail, an auxiliary tool supporting column removably and rigidly secured to the bed of the machine beneath the work table and extending vertically to a position adjacent and above the table, a tool supporting saddle carried by the column, a tool holder carried by the saddle, a vertically extending screw on the column operatively connected to the saddle, a vertically extending shaft on the column operatively connected to the tool holder, and power operated means for rotating the screw and shaft for moving the 115 120 125 130

saddle vertically on the column and the tool holder in the saddle respectively either simultaneously or independently.

5. An auxiliary tool support for boring mills and the like comprising the combination of a base portion provided with a supporting face adapted to be removably and rigidly secured to a supporting cheek on the bed of a machine beneath the work table

10 thereon, a column portion adapted to extend vertically to a position adjacent and above the work table and to movably support a tool saddle thereon, power means thereon, and power operated means for moving the

15 saddle.

6. An auxiliary tool support for boring mills and the like comprising the combination of a base portion adapted to be removably and rigidly secured to the bed of a

20 machine beneath the work table thereon, a column portion adapted to extend vertically to a position adjacent and above the work table and to movably support a tool saddle thereon, power means thereon, and mecha-

25 nism on the tool support for feeding the saddle and tool holder either simultaneously or independently.

7. An auxiliary tool support for boring mills and the like comprising the combination of a base portion adapted to be remov-

ably and rigidly secured to the bed of a machine beneath the work table thereon, a column portion adapted to extend vertically to a position adjacent and above the work table and to movably support a tool saddle 35 thereon, and mechanism including a feed motor on the support for feeding the saddle vertically on the column and the tool holder horizontally in the saddle.

8. An auxiliary tool support for boring 40 mills and the like comprising the combination of a base portion adapted to be removably and rigidly secured to the bed of a machine beneath the work table thereon, a column portion adapted to extend upwardly 45 to a position adjacent and above the work table, a tool supporting saddle carried by the column, a tool holder carried by the saddle, a vertically extending screw on the column operatively connected to the saddle, 50 a vertically extending shaft on the column operatively connected to the tool holder, power means on the column, and means operated therefrom for rotating the screw and shaft for moving the saddle vertically 55 on the column and the tool holder in the saddle respectively.

In testimony whereof, I hereto affix my signature.

JAMES K. CULLEN.
